5 Claims. (Cl. 4—160)

ABSTRACT OF THE DISCLOSURE

A sauna bath unit with an electrical heater mounted in a vertical plane in a rectangular recess of the door. The heater is characterized by a vertically mounted sheet-metal flat rectangular inner housing surrounding the heating elements contained therein and spaced from the walls thereof. The heater is fully open at the top and is further enclosed by an outer housing which is spaced from the inner housing to maintain an annular space therebetween in direct communication with the atmosphere surrounding the associated room by way of lower port means whereby the air in the interior of the room circulates by convection past the heating elements to heat said room.

The present invention relates to a heat sauna and especially an apparatus for generating warm air in a heat room of limited volume.

The present invention generally comprises a heating element, an inner jacket surrounding the heating element, and an outer jacket surrounding the inner jacket in spaced relationship. The inner jacket is open at its upper end and on the front wall near its lower end and is in direct communication with the heat sauna room. The outer jacket is open on the front wall near its upper and lower ends to communicate with the heat room and is also provided with means at its lower end, providing direct communication with the outer atmosphere.

It is therefore an object of the present invention to provide an apparatus for generating heat in a heat sauna room of relatively small volume which does not reduce the available space within the room.

Another object of the invention is to provide a heat-generating device which the user of the room can contact without the danger of injury due to burns.

A further object of the present invention is to provide an apparatus which will enable the maintenance of the desired air humidity in a heat sauna room.

Yet another object of the present invention is to provide a heat-generating device which may be readily and economically produced.

According to the present invention, the above objects are achieved by situating the inventive heat-generating apparatus in the door of the heat room. The annular space between the two jackets of the apparatus is placed in direct communication with the atmosphere surrounding the heat room. An access port is located in such a way that the surrounding atmosphere is caused to flow through the annular space into the heat room and to thereby cool the outer jacket. Further, in the upper and lower portions of the annular space, the atmospheric air is caused to be mixed with the air flowing from the heat room through the inner jacket so that the maintenance of the desired air humidity in the heat room is ensured.

The means for accomplishing the foregoing objects and other advantages, which will be apparent to those skilled in the art, are set forth in the following specification and claims and are illustrated in the accompanying drawings dealing with a basic embodiment of the present invention. Reference is made now to the drawings in which:

2

FIG. 1 shows an exterior view of a heat room fitted with the present invention;

FIG. 2 illustrates the heat room with the door open revealing the inventive apparatus; and

FIG. 3 shows the inventive heat apparatus in perspective view and partly in section.

Referring to the drawings, a heat sauna room 1 is constructed of a permanent or a suitably portable cabinet provided with a door 2 and shelves 3. As is more readily apparent in FIG. 2, the inventive heat-generating apparatus is mounted in the lower portion of the door 2. The inventive apparatus is shown in further detail in FIG. 3.

The inventive heat apparatus generally comprises an electrical heater element 9 contained within an inner jacket 4. The inner jacket is of a generally rectangular cross section and has, adjacent its lower end, an inlet opening 5 while the upper end is completely open.

An outer jacket 6 is so situated as to surround the inner jacket while being spaced therefrom. The outer jacket has on the interior side lower and upper openings 7 and 8, respectively, which may be suitably covered with grids or the like. The dimensions of the outer jacket 6 determine the size of the apparatus and are chosen so that a major portion of the apparatus will be accommodated within the thickness of the door 2.

When the apparatus is mounted in the door, the electrical heating element 9 will heat the air in the heat room by convection with the air flowing from the room, through the openings 7 and 5, upwards through the inner jacket past the heating element and back to the room through the upper opening 8.

As seen in FIGS. 1 and 3 the outer jacket 6 has adjacent the lower end on the side opposite the opening 7 at least one port 10 which is in direct communication with the outer atmosphere. When the apparatus is mounted in the door, the ports 10 open on the outer side as may be seen in FIG. 1. By virtue of the above-described arrangement of the outer ports 10, the cool outer air will flow into and through the annular space between the jackets 4 and 6 thereby cooling the outer jacket 6 and preventing excessive heating of the door material surrounding the apparatus. The bather will thus be insured against burns from accidental contact with the portion of the apparatus which is exposed on the inside of the door.

The air supplied through the ports 10 is mixed with the air entering from the heat room particularly at the opening 8 where the warmed air flows back into the room after passing through the inner jacket. The humidity of the air can be maintained at a desired value by controlling the mixture of air by any suitable means such as controlling the opening of port 10 or controllable flap means in opening 8. A further humidity control such as adjustable port 11 in the upper portion of the door 2 may be provided to place the room in communication with the ambient air. By controlling the passage of air through the port, the bather himself may control the air humidity to some extent.

The invention may be embodied in other specific forms without departing from the spirit or essential characteristics thereof. The present embodiment is therefore to be considered in all respects as illustrative and not restrictive, the scope of the invention being indicated by the appended claims rather than the foregoing description, and all changes which come within the meaning and range of equivalency of the claims are therefore to be embraced therein.

1. A sauna comprising in combination a room,

a door leading into said room and having inner and outer sides with a generally rectangular recess on said

inner side on a lower portion thereof and with lower port means leading through said door into said recess near the bottom of said recess and with upper port means leading through said door near the top thereof well above said recess, 5
 a heater mounted in said recess and comprising, an electrical heating element mounted in a vertical plane, 10
 a vertically mounted sheet-metal flat rectangular inner housing surrounding said heating element and spaced therefrom and having a front wall facing the room, an imperforate rear wall facing away from the room, imperforate side walls joining the front and rear walls, a closed imperforate bottom wall, and fully open at the top, 15
 an outer vertically mounted sheet metal housing filling said recess and projecting into said room therefrom and surrounding said inner housing and spaced therefrom to define a vertically extending annular space therebetween, said outer housing having a rear wall that is imperforate except for openings aligned with said lower port means, imperforate side and bottom walls, and a front wall having a lower grille portion at the bottom and an upper grille portion at the top, said top wall being imperforate as to the portion in 20
 said recess and having a grille portion outside said recess and in said room where said door is closed, said inner housing having an opening in its front wall facing and one the same level as said lower grille and having its open top adjacent the lower extremity of 25
 said upper grille, said inner housing having an inclined baffle integral with said rear wall extending at an angle over said open top toward the corner edge where said upper grille meets the grille portion of the top wall of the outer housing, 30
 the flat annular space between said housings being in direct communication with the atmosphere surrounding the room through said lower port means, the air in the interior of said room circulating by convection through said lower grille, said inner housing 35
 past said heating element and through said outer grille to heat said room, 40
 said air from the surrounding atmosphere passing through said lower port means into the space between said housing rear walls and through said grille portion of said outer housing's top wall into the interior of said room, said air from the atmosphere cooling said outer housing's rear wall and side walls, said upper port means freeing said room from excess pressure, 45
 2. A sauna according to claim 1 wherein said upper port means is adjustable in area, 50
 3. A sauna heater for mounting in a recess in a wall or door of a sauna room, comprising:
 an electrical heating element mounted in a vertical plane, 55
 a vertically mounted sheet-metal flat rectangular inner housing surrounding said heating element and spaced therefrom and having a front wall, an imperforate

rear wall, imperforate side walls joining the front and rear walls, a closed imperforate bottom wall and fully open at the top, 5
 an outer vertically mounted sheet metal housing for filling a said recess and projecting therefrom, surrounding said inner housing and spaced therefrom to define a vertically extending annular space therebetween, said outer housing having a rear wall that is imperforate except for lower opening means, imperforate side and bottom walls and a front wall having a lower grille portion at the bottom and an upper grille portion at the top, said top wall being imperforate as to the portion in said recess and having a grille portion outside said recess, 10
 said inner housing having an opening in its front wall facing said lower grille and having its open top adjacent the lower extremity of said upper grille, said inner housing having an inclined baffle integral with said rear wall extending at an angle over said open top toward the corner edge where said upper grille meets the grille portion of the top wall of the outer housing, 15
 the annular space between said housings being adapted for direct communication with the atmosphere surrounding the sauna room through said lower opening means, 20
 said heater circulating the air in the interior of said room by convection through said lower grille, said inner housing past said heating elements and through said outer grille to heat said room, 25
 4. The heater of claim 3 having means for controlling the amount of air passing through said annular space, 30
 5. The heater of claim 3 having means for controlling the heating of the air in said heater, including means for controlling said heating element and means for controlling the flow of air through said inner housing, said two means for controlling being adjustable both individually and in combination, 35

UNITED STATES PATENT OFFICE
CERTIFICATE OF CORRECTION

Patent No. 3,394,412

July 30, 1968

Tor Olssen

It is certified that error appears in the above identified patent and that said Letters Patent are hereby corrected as shown below:

Column 1, lines 27, 28, 35, 37, 41, second occurrence, 49, 55, 58, 60, 63, and 65, and column 2, lines 1, 3, 5, 7, 14, 28, second occurrence, and 47, cancel "heat", each occurrence. Column 3, line 27, "where" should read -- when --; line 29, "one" should read -- on --.

Signed and sealed this 24th day of February 1970.
